(57) **CLAIM**

The ornamental design for a console for an elastography apparatus, as shown and described.

DESCRIPTION

FIG. 1 is a top, left, front perspective view of my design of the apparatus;

FIG. 2 is a bottom, right, rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded view of the design as shown in FIG. 1, showing two cups removed from a holder of the apparatus;

FIG. 10 is top, left, front perspective view of the two cups of the console for an elastography apparatus;

FIG. 11 is a bottom, right, rear perspective view thereof;

FIG. 12 is a front view thereof;

FIG. 13 is a rear view thereof;

FIG. 14 is a left view thereof;

FIG. 15 is a right view thereof;

FIG. 16 is a top view thereof;

FIG. 17 is a bottom view thereof;

FIG. 18 is a front view of a top, left, front perspective view of the holder of the console for an elastography apparatus shown without the two cups attached;

FIG. 19 is a bottom, right, rear perspective view thereof;

FIG. 20 is a front view thereof;

FIG. 21 is a rear view thereof;

FIG. 22 is a left view thereof;

FIG. 23 is a right view thereof;

FIG. 24 is a top view thereof; and,

FIG. 25 is a bottom view thereof.

The broken lines depict portions of the console for an elastography apparatus that form no part of the claimed design. The dot-dash lines in FIG. 9 show the order of assembly of the claimed design and also form no part thereof.

1 Claim, 22 Drawing Sheets
